FREDERICK A. FELDKAMP, OF NEWARK, NEW JERSEY, ASSIGNOR OF ONE-HALF TO
RUDOLF H. AMBERG, OF BLOOMFIELD, NEW JERSEY.

INCANDESCENT LAMP.

Application filed September 26, 1918. Serial No. 326,466.

To all whom it may concern:

Be it known that I, FREDERICK A. FELDKAMP, a citizen of the United States, residing at Newark, in the county of Essex and State 5 of New Jersey, have invented certain new and useful Improvements in Incandescent Lamps; and I do hereby declare the following to be a full, clear, and exact description of the invention, such as will enable others 10 skilled in the art to which it appertains to make and use the same, reference being had to the accompanying drawings, and to characters of reference marked thereon, which form a part of this specification.

15 The present invention relates, generally, to improvements in incandescent electric lamps; and the invention has reference, more particularly, to a novel construction of double filament lamp provided with an automatic means operating to bring into the lamp circuit one filament after the other filament has burned out or broken.

The invention has for its principal object 20 to provide a novel construction of double filament incandescent lamp having a novel automatic switching mechanism for inserting operatively into the lamp circuit one filament, and upon the burning out of said filament automatically bringing into the 25 lamp circuit the second filament, whereby either the life length of the lamp as a whole is doubled, or the efficiency of the lamp in its lighting effects is greatly increased with a life length substantially that 30 of a single filament lamp.

Other objects of the present invention, not at this time more particularly enumerated, will be clearly understood from the following detailed description of the same.

40 With the various objects of the invention in view, the same consists, primarily, in the novel construction of incandescent lamp hereinafter set forth; and the invention consists, furthermore, in the novel arrangements 45 and combinations of the various devices and parts, as well as in the details of the construction of the same, all of which will be hereinafter more fully described, and then finally embodied in the appended claims.

50 The invention is clearly illustrated in the accompanying drawings, in which:—

Figure 1 is an elevation of my novel incandescent lamp, a portion of the enclosing bulb being shown in section, the same illustrating the automatic switch mechanism as

normally arranged to hold in the lamp circuit for service one of the two filaments employed therewith; Figure 2 is a similar view illustrating the switch mechanism, as automatically operated upon the burning out of 60 the first filament, serving to switch into the lamp circuit for service the second filament. Figure 3 is a detail view, similar to that shown in Figure 1, but illustrating a slightly modified form of automatic switch mechanism. Figure 4 is a diagram illustrating the electrical arrangement and operative relation of the switching mechanism to the two filaments of the lamp.

Similar characters of reference are employed in all of the hereinabove described views, to indicate corresponding parts.

Referring now to said drawings, the reference-character 1 indicates the usual glass bulb which encloses the filaments, the same 75 being provided with the usual screw-threaded plug 2 and center button contact 3 for insertion in a socket to electrically connect the leading-in wires 4 and 5 of the lamp in the operating electric supply circuit. Mounted to extend upwardly within the interior of the bulb 1 is the hollow glass stem 6 through which the said wires 4 and 5 extend, said glass stem 6 carrying an upwardly extending supporting post or rod 7 of glass 80 for supporting the filaments within the bulb.

Two filament members are supported from said supporting post or rod 7 by bracket pieces 8 which are fused into said post or rod so as to radiate therefrom, each of said 90

filament members being electrically connected on one side to the leading-in wire 4 by means of the interconnecting wire conductor 9. The filament member to be first used in service comprises a two branch filament, to 95 wit, the filament branch 10 and the filament branch 11, each branch being of one-half the total candle power and wattage desired of the complete filament member, but each branch being capable of operating at the 100 line voltage intended for the complete filament member. The said branches 10 and 11 are respectively connected, by the ends thereof opposite the ends connected with said

leading-in wire 4, to the upper end of a conducting wire and support 12 which extends downwardly to terminate in a lateral foot-piece 13 secured to said post or rod 7. The second filament member, or that to be used in service after said first filament member 110

- burns out or is broken, comprises a single branch filament 14 of the full candle power and wattage desired, and capable of operating at the intended line voltage. The end 5 of said filament 14, opposite to that connected with said leading-in wire 4, is connected to the upper end of a conducting wire and support 15, which extends downwardly to terminate in a lateral foot piece 16 secured to said post or rod 7. Said conducting wire and support 15 is substantially parallel to said conducting wire and support 12, but is outwardly and laterally offset from the latter.
- 15 Mounted on said glass stem 6 by means of a suitable embracing clamp device 17 is an upwardly extending spring-arm 18 terminating at its upper or free end in a lateral or transverse contact arm 19, which, when the 20 spring-arm is held under tension, is caused to electrically contact with or engage said conducting wire and support 12, to connect said first filament member through said spring arm, which is a conductor, with the 25 leading-in wire 5, the latter being electrically conducted with said spring-arm by means of an interconnecting wire conductor 20 and said contact arm 19, when the spring-arm is released, is caused to electrically contact with or engage said conducting wire and support 15, to connect said second filament member with said leading-in wire 5. Said spring-arm 18 is compounded with an 30 auxiliary or secondary spring-arm 21, the base of the latter being suitably secured to the body of said main spring-arm 18, so that said auxiliary or secondary spring-arm 21 extends upwardly beyond the location of said contact-arm 19 of said main spring-arm. The upper or free end of said auxiliary or secondary spring-arm is provided 35 with a coating of insulating material, such, for example, as the bead 22 of glass, or similar material.
- 40 45 The branch 10 of said first filament member is tapped midway between its ends by a tap-wire 23, and the branch 11 of said first filament member is tapped midway between its ends by a tap-wire 24. Connected with 50 and extending outwardly from said post or rod 7 is a bracket piece 25 to which one end of a fuse link or wire 26 is anchored and at the same time electrically connected with said tap-wire 23, and also connected with 55 and extending oppositely outward from said post or rod 7 is another bracket piece 27 to which the opposite end of said fuse link or wire 26 is anchored and at the same time electrically connected with said tap-wire 24.
- 60 Said fuse link or wire 26 extends around the insulating bead 22 of said auxiliary spring-arm 21, holding the latter under tension, and at the same time holding the main spring-arm 18 under tension and in position 65 to electrically engage the contact-arm 19

with the wire and support 12, thus switching into and maintaining in service the first filament member, while the circuit through the second filament is interrupted to render the latter inoperative or out of service. The 70 purpose of the auxiliary spring-arm 21 is to provide a means for compensating any slight release of the tension, under which the main spring-arm 18 is to be held in order to maintain the contact arm 19 in operative electrical engagement with the wire and support 12, which might be caused by slight expansion or elongation of the fuse link or wire under the normal temperature increase within the bulk when the lamp is lighted, and which, 80 did not the auxiliary spring-arm 21 compensate for, might result in the separation of the contact arm 19 from the wire and support 12 thereby interrupting the circuit through the first filament member, without 85 fully releasing the spring-arm 18 to carry the contact-arm 19 into circuit closing relation to the wire and support 15 and second filament member.

The lamp constructed, as above described, 90 is intended to operate as follows:—Normally the first filament is held in circuit and consequently in service. The current flows through the two branch filaments 10 and 11, which being of equal capacity and resistance carry the current flow so equally that there exists no tendency of the current to shunt through the fuse link or wire 26 by way of the tap wires 23 and 24, and consequently the fuse link or wire remains intact 95 and serves its purpose of mechanically tying back the spring-arms 18 and 21 in the position completing the circuit through said first filament member. If, however, the first filament breaks in either of its branches 10 or 105 11 (by reason of burning out or from other causes), then the balance of current flow through the said filament branches 10 and 11 is disturbed so that some of the current is passed through the fuse link or wire 26, 110 causing the latter to immediately blow and break so that the spring-arms 21 and 18 are released, whereby the spring-arm 18 swings outward, under the impulse of its tension, to carry the contact-arm 19 away from the 115 wire and support 12 and into electrical engagement with the wire and support 15 so that the second filament member is immediately switched into circuit and service, and the life of the lamp is thereby extended.

In order to provide a clear understanding of the electrical operations and functioning involved in my present invention, reference may be had to the diagram shown in Figure 4. As indicated in said diagram, current normally flows through 9—10—11—12—18, this flow being balanced in the branches 10 and 11 so that no current flows through 23—26—24. Assume, however, that the first filament member breaks in branch 10 at 120 130

—a—, then it is evident that the current will flow from 9 to 12—18 through c—d of branch 11, and also through c—24—26—23—b. If the break occurs in branch 10 at 5—b— then the current will flow through c—d, and also through a—23—26—24—d. If the break occurs in branch 11 at —c—, then the current will flow through a—b, and also through a—23—26—24—d; and finally, 10 if the break occurs in branch 11 at —d—, then the current will flow through a—b, and also through c—24—26—23—b. It is therefore apparent that any of these breaks will cause a blowing of the fuse link or wire 26, 15 since the current passed therethrough will be sufficient for that purpose. The amount of current rendered available for blowing the fuse link or wire 26 may be exemplified by the following instance, based on the performance of a 200 watt—100 volt lamp.

Assuming that the combined amperage of the two branched filament 10—11 is 2 amperes. The resistance of each branch 10 and 11 respectively, is 100 ohms, and consequently for each part a, b, c and d is 50 ohms. If the two branches 10 and 11 respectively operate properly, they each consume 1 ampere at 100 volts. In the event a break occurs in any of the portions a, b, c or d of 25 the said branches 10 and 11, it follows, that there will always be two portions of 50 ohms each in parallel, connected in series with one portion of 50 ohms. The resistance of such a series or combination therefore 30 will be 25 plus 50 or 75 ohms. This means that there are 1.33 amperes flowing, and one-half of this amount will pass through the fuse link or wire 26, which is selected accordingly to blow under such a condition. 35 Of course, there is a small discrepancy in the example given, as after the break the temperature of the branches of filaments in series is not alike. The two branches in parallel are under normal and consequently 40 their resistance is less, and the single remaining branch in series with the latter is overloaded, therefore its resistance is higher. While this condition tends to counterbalance, yet there is a change from initial 45 normal condition in the series which will be sufficient to blow the fuse link or wire 26 selected to meet the condition. The fuse link or wire 26 should be very fine so that the current under the conditions mentioned 50 will operate it, due consideration being had for the mechanical purpose of retaining the spring switch-arm in normal position.

Instead of the compound spring switch-arm, above described I may use a single spring switch-arm, such as the simple spring member 28, shown in Figure 3 of the drawings, the same being provided with contact elements or lateral arms 29 and 30 for respectively engaging the supporting conductors 55 12 and 15 of the respective filaments.

While I have illustrated my invention with the switching mechanism arranged within the bulb, it will be clearly evident that the scope of my present invention will also include its location outside the bulb 70 proper, suitable connections between the same and the filaments being provided.

I claim:—

1. In an incandescent lamp, the combination with a plurality of filaments having on 75 one side a common connection with one pole of the lamp, the first filament comprising a balanced two-branched filament the branches of which are in parallel, a spring switch means in connection with the other pole of 80 the lamp, a fuse link arranged to normally hold said spring switch means in circuit closing engagement with said first filament, and tap wires connecting the ends of said fuse link respectively with intermediate portions 85 of said first filament branches, said spring switch means when released by the breaking of said fuse link being adapted to move into circuit closing engagement with the next 90 filament.

2. In an incandescent lamp, the combination with a plurality of filaments, a non-conducting supporting rod from which said filaments are supported, a conducting means serving as a common connection between one 95 side of said respective filaments and one pole of said lamp, a supporting conductor secured to said supporting rod for connection with the opposite side of the first filament, a second supporting conductor secured to said supporting rod for connection with the opposite side of the second filament, a spring switch means in electrical connection with the other pole of the lamp, a fusible means 100 for holding said switch means in circuit closing engagement with the supporting conductor of said first filament, and means for shunting current through said fusible means upon the breaking of said first filament whereby said fusible means breaks to 105 release said switch means for circuit closing engagement with said supporting conductor of said second filament.

3. In an incandescent lamp, the combination with a plurality of filaments, a non-conducting supporting means from which said filaments are supported, a conducting means serving as a common connection between one side of each filament and one pole of said lamp, a supporting conductor secured to said supporting means for connection with the opposite side of said first filament, a second supporting conductor secured to said supporting means for connection with the opposite side of the second filament, a spring switch-arm secured to said supporting means and electrically connected with the opposite pole of said lamp, a fuse link, means for supporting said fuse link from said supporting means, said fuse 115 120 125 link from said supporting means, said fuse

- link engaging the free end of said switch arm to hold the same under stored tension and in circuit closing engagement with said supporting conductor of said first filament,
- 5 means for electrically insulating said switch arm from said fuse link, said first filament comprising a balanced two-branched filament the branches of which are connected in parallel between said common
- 10 conducting means on one side and said first supporting conductor on the other side, and tap wires connecting the ends of said fuse link respectively with points intermediate the ends of each branch of said first filament
- 15 to provide balanced filament portions on each side of each tap wire so that the breaking of any portion of either filament branch will shunt current through said fuse link to blow the same thereby releasing said switch
- 20 arm for movement into circuit closing engagement with said supporting conductor of said second filament.
4. In an incandescent lamp, the combination with a plurality of filaments, a non-conducting supporting means from which said filaments are supported, a conducting means serving as a common connection between one side of each filament and one pole of said lamp, a supporting conductor secured to said supporting means for connection with the opposite side of said first filament, a second supporting conductor secured to said supporting means for connection with the opposite side of the second filament,
- 25 a spring switch arm secured to said supporting means and electrically connected with the opposite pole of said lamp, the free end of said switch arm having contact means, a secondary spring arm anchored upon said
- 30 switch arm, a fuse-link, means for supporting said fuse link from said supporting means, said fuse link engaging the free end of said secondary spring-arm to hold same and said switch arm under stored tension
- 35 and the latter in circuit closing engagement with said supporting conductor of said first filament, said secondary spring arm serving to compensate any elongation of said fuse link due to expansion by heat, means for
- 40 electrically insulating said secondary spring arm from said fuse link, and means for electrically connecting said fuse link with said first filament so that breaking of the latter will shunt current through said fuse link
- 45 to blow the same thereby releasing said switch arm for movement into circuit closing engagement with said supporting conductor of said second filament.
5. In an incandescent lamp, the combination with a plurality of filaments, a non-conducting supporting means from which said filaments are supported, a conducting means serving as a common connection between one side of each filament and one
- 55 pole of said lamp, a supporting conductor secured to said supporting means for connection with the opposite side of said first filament, a second supporting conductor secured to said supporting means for connection with the opposite side of the second filament,
- 60 a spring switch arm secured to said supporting means and electrically connected with the opposite pole of said lamp, the free end of said switch arm having contact means, a secondary spring arm anchored upon said
- 65 switch arm, a fuse-link, means for supporting said fuse link from said supporting means, said fuse link engaging the free end of said secondary spring-arm to hold same and said switch arm under stored tension
- 70 and the latter in circuit closing engagement with said supporting conductor of said first filament, said secondary spring arm serving to compensate any elongation of said fuse-link due to expansion by heat, means for
- 75 electrically insulating said secondary spring arm from said fuse link, and means for electrically connecting said fuse link with said first filament so that breaking of the latter will shunt current through said fuse-link to blow the same thereby releasing said switch arm for movement into circuit closing engagement with said supporting conductor of said second filament.
6. In an incandescent lamp, the combination with a pair of filaments of means for connecting the latter with one pole of said lamp, a spring switch arm electrically connected with the opposite pole of said lamp, means connected with each filament for receiving the circuit closing engagement of said switch arm therewith, a fuse-link, means for supporting said fuse-link, said fuse-link normally engaging said switch arm to hold the same under stored tension and in circuit closing relation to the first filament, means for insulating said fuse-link from said switch arm, and means for electrically connecting said fuse-link with said first filament so that breaking of the latter will shunt current through said fuse-link to blow the same thereby releasing said switch arm for movement into circuit closing relation to the second filament.
7. In an incandescent lamp, the combination with a pair of filaments of means for connecting the latter with one pole of said lamp, a spring switch arm electrically connected with the opposite pole of said lamp, means connected with each filament for receiving the circuit closing engagement

of said switch arm therewith, a secondary spring arm anchored upon said switch arm, a fuse-link, means for supporting said fuse-link, said fuse-link engaging the free end of 5 said secondary spring arm to hold the same and said switch arm under stored tension and the latter in circuit closing relation to the first filament, said secondary spring arm serving to compensate any elongation of 10 said fuse-link due to expansion by heat, means for electrically insulating said secondary spring arm from said fuse-link, and means for electrically connecting said fuse-

link with said first filament so that breaking of the latter will shunt current through said 15 fuse-link to blow the same thereby releasing said switch arm for movement into circuit closing relation to the second filament.

In testimony that I claim the invention set forth above I have hereunto set my hand 20 this 25th day of September, 1919.
